UNITED STATES PATENT OFFICE.

EARL E. WRIGHT, OF ROCHESTER, PENNSYLVANIA, ASSIGNOR OF ONE-HALF
TO PHILLIP LEE, OF ROCHESTER, PENNSYLVANIA.

DRIVING-GEAR FOR MOTOR-VEHICLES.

SPECIFICATION forming part of Letters Patent No. 703,881, dated July 1, 1902.

Application filed September 26, 1901. Serial No. 76,601. (No model.)

To all whom it may concern:

Be it known that I, EARL E. WRIGHT, a citizen of the United States, residing at Rochester, in the county of Beaver and State of Pennsylvania, have invented certain new and useful Improvements in Driving-Gear for Motor-Vehicles, of which the following is a specification, reference being had therein to the accompanying drawings, forming part of this specification, in which—

Figure 1 is a view in side elevation of my improved front-axle-driving gear, showing the connection thereto from the motor sprocket-wheel. Fig. 2 is a front elevation of the front running and driving gear. Fig. 3 is a plan view of Fig. 1, partially in section, as indicated by the line III III of Fig. 2. Fig. 4 is a detail view, in side elevation, of the pivoted wheel-supporting bracket. Fig. 5 is an end view thereof. Fig. 6 is a detail view, in front elevation, of the main supporting-framework.

My invention relates to improvements in motor-vehicles; and it consists in the means for imparting driving motion to the front axle, so as to propel the vehicle by traction, whereby motion may be transmitted from a rigid axle through universal gearing to the wheels at whatever angle they may be located.

Referring now to the drawings, 2 is the front axle or shaft of a vehicle, mounted in bearings 3 of the main frame 4, upon which is supported in any suitable or desired manner the forward portion of the vehicle-body. (Not shown.) The frame 4 is provided at each end, above and below the axle-bearing 3, with brackets 5, terminating in bearings 6 above and below, in which is mounted the pivotal spindle or shaft 7, carrying the intervening bevel-wheel 8. Upon the spindle or shaft 7 is pivotally mounted at each end by bearings 9 the upper and lower ends of bracket 10, the middle portion of which is in alinement with the axle 2 and is provided with a boss 11, in which is mounted the axle or skein 12, carrying the wheel 13.

Upon each outer end of the axle 2 is mounted a driving bevel-wheel 14, the bracket 5 having an upwardly-extending bearing 15, in which the end of the axle is supported beyond such bevel-wheel. The bevel 14 meshes into bevel 8, mounted upon spindle 7, which bevel 8 likewise meshes into another bevel-wheel

16, fixedly secured to the hub of wheel 13, and as thus constructed it will be seen that motion will be transmitted from the axle or shaft 2 through the bevel-gearing to the front wheel of the vehicle at whatever position the vehicle-wheels may be, as in turning a curve. The bracket 10 is provided with an opening 17 to provide clearance for the bevel-wheel 8 and is also provided with a backward or forward extension 18, with which connection may be made with the steering-gear 19 in any suitable or preferred manner.

A represents the driving-pinion of the motor of the vehicle, which may be utilized to drive the front axle alone or both front or back, and when the apparatus is designed to be used as an auxiliary to a back-axle-driven vehicle it becomes necessary to use the intermediate-driven sprocket-wheel 20, geared by chain 21, and the driving-pinion 22, meshing into driven pinion 23, mounted upon the axle 2, which axle must rotate backwardly in order to transmit forward motion to the traction-wheels through the bevel-gearing. When, however, it is desired to gear direct to the front axle, the driving-pinions 22 and 23 may be dispensed with, sprocket-wheel 20 being mounted on, and the motor geared direct to, the front axle, the motor in such case being reversed.

While I have described the construction and mode of operation at one end only of the shaft 2, it will be understood that, as shown in the drawings, this construction is in duplicate at each end and corresponds in construction and mode of operation in all respects.

It will be understood that the frame 4 may be designed for such alternative driving arrangement or may be made in any other suitable or desired manner, according to the proportions or other details of construction of the vehicle.

While my invention is particularly adapted to be used with motor-vehicles or automobiles, it is equally well adapted to power-driven mowers, reapers, binders, &c., or other similar vehicles or apparatus.

Various changes or modifications may be made in the design, proportions, or arrangement or other features or details by the

skilled mechanic without departing from my invention, since I do not desire to be limited to the exact construction shown and described, but to include all such changes and variations as within the scope of the following claims.

What I claim is—

1. In driving mechanism for motor-vehicles, the combination of a main framework, a rotatable shaft mounted in bearings therein provided with bevel-wheels at each end, traction-wheel bracket-bearings pivotally mounted in each outer end of the framework provided with clearance - openings, traction-wheels rotatably mounted on said bearings provided with bevel-wheels, pivotal shafts connecting the traction-wheel bracket-bearings with the main frame and carrying bevel-wheels intermeshing with the driving and driven bevel-wheels and extending through said clearance-openings, with means for transmitting motion to the main shaft.
2. In driving mechanism for motor-vehicles, the combination of a main framework, a rotatable shaft mounted in bearings therein provided with bevel-wheels at each end, supplemental shaft-bearings outside of the driving-bevels, traction-wheel bracket-bearings pivotally mounted in each outer end of the framework provided with clearance - openings, traction-wheels mounted thereon pro-

vided with bevel-wheels, pivotal shafts connecting the traction-wheel bracket-bearings, with the main frame and carrying bevel-wheels intermeshing with the driving and 35 driven bevel-wheels and extending through said clearance-openings, with means for transmitting motion to the main shaft.

3. In driving mechanism for motor-vehicles, the combination of a main framework, a 40 rotatable shaft mounted in bearings therein provided with bevel-wheels at each end, traction-wheel bracket-bearings pivotally mounted in each outer end of the framework provided with clearance-openings, and having 45 extended steering-arms with steering mechanism connected thereto, traction-wheels rotatably mounted on said brackets provided with bevel-wheels, pivotal shafts connecting the traction-wheel bracket-bearings with the 50 main frame and carrying bevel-wheels intermeshing with the driving and driven bevel-wheels and extending through said clearance-openings, with means for transmitting motion to the main shaft.

In testimony whereof I affix my signature in presence of two witnesses.

EARL E. WRIGHT.
